UNITED STATES PATENT OFFICE.

HENRY L. FERRIS, OF HARVARD, ILLINOIS, ASSIGNOR TO HUNT, HELM, FERRIS & CO., OF HARVARD, ILLINOIS, A CORPORATION OF ILLINOIS.

HAY-CARRIER.

SPECIFICATION forming part of Letters Patent No. 731,558, dated June 23, 1903.
Application filed February 11, 1903. Serial No. 142,929. (No model.)

To all whom it may concern:

Be it known that I, HENRY L. FERRIS, a citizen of the United States of America, residing at Harvard, in the county of McHenry 5 and State of Illinois, have invented certain new and useful Improvements in Hay-Carriers, of which the following is a specification.

My invention relates to certain new and useful improvements in hay-carriers; and its 10 object is to produce a device of this class which shall be simple, cheap, and efficient and which shall have certain other advantages which will appear in the course of this description.

15 To these ends my invention consists in certain novel features of construction which are clearly described in this specification and illustrated in the accompanying drawings.

In the aforesaid drawings, Figure 1 is a side 20 elevation of my improved carrier. Fig. 2 is a similar view showing the outer casing cut away in the line 2 2 of Fig. 3, certain parts being in a different position. Fig. 3 is an end elevation of my improved carrier. Fig. 25 4 is a section in the line 4 4 of Fig. 1 looking in the direction of the arrow, and Fig. 5 is a section in the line 5 5 of Fig. 1 looking downward.

Referring to the drawings, A is a suitable 30 track, upon which run pulleys B, which are journaled upon the upper part c^3 of the hanger-frame. This part of the frame C, as clearly indicated in Figs. 3 and 4, consists of a single piece of metal cast with a hemispheroidal portion c and outwardly-projecting arms c' , to which are immediately connected the pulleys. This hemispheroidal portion c is provided with an outwardly-turned bead c^2 .

The lower part of the main frame of the 40 device is composed of two substantially similar portions D, each of which consists primarily of a hollow segment of a sphere d and a substantially flat portion cast integral therewith, d' . The two segmental portions d form 45 together substantially a hollow hemisphere provided with a longitudinal slot. The upper edge of the hemisphere is provided with an outwardly-turned flat portion d^2 , an upwardly-turned rim d^3 , and an inwardly-turned 50 lip d^4 , which overhangs the outwardly-turned bead c^2 , heretofore described. The parts are

assembled before the two members D D are secured together, which is later effected by means of rivets d^5 passing through them.

It will be observed that the lower portion 55 of the main frame is rotatable upon the upper portion, the bearing being between the outwardly-turned bead c^2 of the upper portion and the adjacent parts of the lower portion. A spring-pressed catch E is provided 60 in one of the portions D and engages with the upper portion of the frame to lock the two parts normally together in the position shown in the drawings, wherein the normal line of the track A lies substantially in the 65 plane of the flat portions D.

Between the two portions D of the frame is journaled a pulley F. A second pulley G runs upon a pin g , which pin also connects two arms H, pivoted to the frame, to links I. 70 The links I in turn are pivotally connected to a jaw J, which extends almost across the entire frame and is pivoted at the opposite end thereof. It will be noted, therefore, that the pulley G can oscillate in a vertical plane, 75 any weight which may be thrown upon the pulley tending to draw down the jaw J. Over the pulleys F and G runs a rope K, attached at one end to a hay-sling pulley-block L, running thence over the pulley F, thence under 80 the two hay-sling pulleys, and thence over the pulley G and to any suitable source of motive power. The hay-sling pulley-blocks are adapted to carry the sling in the usual manner. The opposite end of the jaw J to its 85 pivot is provided with a curved and pointed end j , which is adapted to press upon the rope K. Opposite the end j on the frame is pivoted a block M, adapted to cooperate with the pointed end j of the jaw to clamp the rope 90 K. This block M is provided with a tooth m and a depression m' , into which the end of the jaw presses the rope. It is also provided with an antifriction-roller m^2 .

The jaw J is provided between its ends with 95 upwardly-projecting arms j^2 , which extend into the hollow of the spheroidal portion of the frame heretofore described, said arms being provided at their upper ends with laterally-extending pins j^3 , which are adapted to 100 engage with an inclined cam a , secured to the track A. It is obvious that when the hay-

carrier comes to the position on the track shown in Fig. 1 the pins j^3 ride up upon the cam a , raise the jaw, and permit the rope to run freely over the pulleys. When the hay-carrier, on the other hand, is in any other position, the jaw itself (when unrestrained by the latching devices, which will hereinafter be described) will fall by its own weight and the weight upon it, so as to come in contact with the rope, and any weight which may be supported by the hay-sling pulleys will be transmitted through the pulley G and links I to the jaw, so as to bring a considerable force to bear upon the rope.

15 A catch N , spring-pressed by a spring n , is provided between the halves of the lower part of the frame, which catch is adapted to engage with the shoulder j^4 of the jaw J to hold it normally in its raised position. To the 20 catch N is secured a contact-piece N' , which when pressed upward will swing the catch upon its pivot, so as to release the jaw. This contact-piece N' is so positioned as to be struck by the pulley-blocks when they rise to 25 their highest point. To the catch is also attached a cord N^2 , which runs over a pulley d^6 , journaled in one of the two halves of the lower part of the frame. This cord is intended for use when for any reason it is desired 30 to release the jaw before the pulley-blocks reach the top of their normal movement. Rigidly attached to the catch N is a trigger O , running outside of the frame and parallel thereto. Any means can be adopted to 35 secure these two parts rigidly together, the device illustrated in the drawings consisting in a squared shaft on the catch, fitting in a corresponding hole in the trigger. To the end of the trigger O is connected a contact-piece 40 o , which surrounds that end of the rope K which is attached to the pulley-blocks, and to the said rope is attached a movable button k , which is adapted to come into contact with the contact-piece o to raise the trigger and 45 swing the catch so as to release the jaw.

The operation of the device will now be described. Starting in the position shown in Fig. 1, wherein the jaw is raised by engagement of the pins j^3 with the cam a or the 50 track, the desired load is attached to the pulley-blocks in the usual manner. The free end of the rope K is then pulled so as to raise the hay-sling pulleys and the load carried thereby, the rope running freely over the 55 pulleys and the antifriction-roller m^2 , and the jaw being held up by engagement with the latch N . When the hay-sling pulleys reach their highest point, the blocks strike the contact-piece N' and release the catch. 60 The hay-carrier has meanwhile been held stationary on the track by engagement of the projecting pins j^3 with a small lug a' , which forms a part of the cam-plate a . This lug is so positioned that it strikes the pins j^3 when 65 they are held in their raised position. When the catch is released by engagement of the pulley-blocks L with the contact-piece N' , the

jaw falls by its own weight and the force exerted upon it by the load on the pulley-blocks L and the pins j^3 fall out of the path of the lug a' . This clamps the rope between the pointed end of the jaw and the block M , and the force exerted upon the rope then pulls the hay-carrier bodily along the track. When the proper position is reached for dumping 75 the hay, the same is dropped in the ordinary way. The carrier as a whole is then returned to its original position without moving the parts by a suitable returning mechanism, (not shown,) and when it reaches this position 80 the jaw is raised by engagement of the pins j^3 with the cam a , the latch swings into its original position by force of the spring n , and the parts are in position to take another load. When it is desired to raise a particular load 85 only part way up or to stop it, the cord N^2 is pulled so as to release the catch N , when the rope is clamped and the carrier moved off as before. When it is desired to raise all the loads in succession only part way and it is 90 desired to dispense with pulling the rope N^2 with each load, the button k is moved up to engage with the contact-piece o on the trigger O at the desired height. It will be seen that when the button is so set on the rope K as to 95 engage with the contact-piece o the catch will be released as soon as the button reaches the contact-piece, thus releasing the catch, clamping the rope, and causing movement of the carrier as before.

The particular advantages of this construction over the structures heretofore in use consist, first, in the fact that the clamping-jaw itself rests upon the cam on the track instead of the jaw being raised by some intermediate 105 mechanism. In a device of this class which must be put on the market for a very low price it is necessary that all the parts be so constructed that they can be cast and assembled without any great amount of finishing. 110 It is necessary, therefore, that as few coacting parts be provided as possible, and every part which is removed constitutes a great improvement. For this reason the fact that the jaw itself is caught by the cam makes this device preferable to others. A second advantage lies in the fact that the latch N acts directly upon the jaw instead of upon some intermediate mechanism. The construction is extremely simple and can be made of cast-iron 120 without finishing, and is therefore much cheaper and desirable than structures wherein a number of coacting parts are provided to latch the jaw in its raised position. A third advantage lies in the fact that when the pulley G swings downward and brings the jaw into contact with the rope it swings not only down, but toward the same vertical line as the tooth of the block M . A bend is therefore made in the rope over the point of the 125 jaw, which affords a very firm hold thereon. Inasmuch as it is necessary to have the rope straight during the raising of the hay-sling, it is particularly advantageous to have the pul-

ley swing in this direction, so as to bend the rope at the only time when such a bend would not be disadvantageous.

While I have described this particular embodiment of my invention in detail, I realize that there are considerable variations in the details of construction which can be made without departing from the spirit of the invention, and I therefore do not intend to limit myself to the particular form except as set forth in the claims.

I claim as new and desire to secure by Letters Patent—

1. In a device of the class described, the combination with a frame and pulleys journaled thereon adapted to run upon a suitable track, of a rope-clamping jaw pivoted on said frame and having a portion adapted to engage a suitable cam to raise the jaw from its clamped position and a spring-pressed catch pivoted to the frame and adapted to secure said jaw in said raised position, substantially as described.

2. In a device of the class described, the combination with a suitable track, a frame provided with pulleys adapted to run thereon, a suitable cam on the track, and a rope running over said pulleys and adapted to receive and support suitable hay-sling pulleys, of a jaw adapted to clamp the rope, means for disengaging the jaw from the rope, and a latch pivoted on the frame and engaging directly with the jaw to lock it in the position where it is disengaged from the rope.

3. In a device of the class described, the combination with a suitable track, a frame provided with pulleys adapted to run thereon, a suitable cam on the track, and a rope

running over said pulleys and adapted to receive and support suitable hay-sling pulleys, of a block secured to the frame, a jaw pivoted on the frame and adapted to coact with the block to clamp said rope, one of the pulleys on the frame being secured to the jaw, whereby the weight of the hay-sling is transmitted to the jaw to aid it in clamping the rope, said pulley being so arranged that when said jaw moves downward, said pulley swings toward the vertical line of said block to bend the rope over the block.

4. In a device of the class described, the combination with a suitable track, a frame provided with pulleys adapted to run thereon, a suitable cam on the track, and a rope running over said pulleys and adapted to receive and support suitable hay-sling pulleys, of a block secured to the frame, a jaw pivoted to the frame and adapted to coact with said block to clamp the rope, and links pivoted together, one pivoted to the jaw between its clamping ends and its pivot, and the other pivoted to the frame near said block, one of the pulleys on said frame over which said rope runs being journaled on the pivot between said two links, whereby when said jaw is moved downward, said pulley swings toward the vertical line of said block to bend the rope over said block.

In witness whereof I have signed the above application for Letters Patent at Harvard, in the county of McHenry and State of Illinois, this 7th day of February, A. D. 1903.

HENRY L. FERRIS.
